UNITED STATES PATENT OFFICE.

ARTHUR H. MERRILL, OF HARTFORD, CONNECTICUT.

KEY CASE.

Application filed December 12, 1923. Serial No. 680,070.

My invention relates to the class of devices for holding and retaining keys, and an object of my invention, among others, is the provision of a case within which the keys 5 may be selectively inclosed, and a further object of the invention is the provision of a case of novel construction for the purpose specified; and a still further object of the invention is the provision of means for 10 loosely attaching the keys in a manner to enable them to be readily accessible for use.

One form of device embodying my invention and in the construction and use of which the objects herein set out, as well as others, 15 may be attained, is illustrated in the accompanying drawings, in which—

Figure 1 is a view of one side of my improved key case with the flaps opened out and showing the keys attached in place. 20 Figure 2 is a view of the opposite side of the case with one of the flaps closed, a key and the means for securing it being shown in dotted lines.

Figure 3 is an edge view of the case with the 25 flaps in opened position.

Figure 4 is a view, scale enlarged, in section through the case on a plane denoted by the dotted line 4—4 of Figure 1 and illustrating the manner of attaching the keys.

Figure 5 is a perspective view of the case 30 shown as closed.

My improved key case is constructed to provide at least two compartments wherein in one compartment a key or keys required 35 for frequent use may be selectively inclosed, and wherein in another compartment other keys not so frequently required for use may be collectively inclosed. This case embodies a selective compartment 6 and a collective compartment 7 and it may be composed of any suitable flexible material, as leather. In the preferred form of construction the selective compartment is closed by a single flap 8 and the collective compartment is closed by 40 a double flap comprising members 9—10, although the arrangement shown may be varied as to the number of flaps as to the different compartments without departing from the spirit and intent of the invention.

In the preferred form of construction and one that I have found to satisfactorily answer my purposes, a back 11 comprising one side of each of the compartments above mentioned is extended and folded at one end to form the 45 flap 10, and the flaps 8 and 9 are composed of a single piece, folded at one edge and

stitched or otherwise secured along said folded edge to the back 11, and as clearly shown in Figure 5 of the drawings. Any suitable means for securing the flaps may be employed, 60 the ordinary form of snap fastener being shown herein for such purpose.

The means for attaching and supporting the keys comprises a supporting bar 13 upon which key supporting links 14 are pivotally mounted, these links comprising key supporting loops 15, and spacers 18 may be employed, located between the links to retain them in properly spaced relations. The bar 13 may be secured to ears 16 overturned from a 70 supporting plate 17 secured to the back in any suitable manner, as by riveting.

Snap hooks 19, of any ordinary form and construction to enable the keys to be readily attached and detached, are loosely secured to 75 the loop 15 of the supporting link, and said links are attached to the bar 13 in a manner to afford considerable play for the links. The snap hooks are attached to the links in a manner to afford much play for the hooks and the 80 attachment of the keys to the snap hooks further provides for considerable play, any of which features of looseness, in whole or in part, provides for such looseness in the mounts for the keys as to enable such keys to assume 85 any of the positions that may be required, as for insertion of a key in a lock.

It will thus be seen that the key 20, that may be required for more frequent use than others, contained in the case may be located in 90 the selective compartment 7, and little trouble will therefore be required to select such key for use whenever it may be required, and being separated from the other keys in the case such other keys will not interfere with the 95 free and unobstructed use of the selected keys.

It will be understood that the means hereinabove described for attaching the keys applies to such means for such attachment in 100 each of the compartments.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out. 105

I claim—

1. A key case formed of flexible material

and embodying two flat sections with one side edge of the first section secured to the second section at a point intermediate its opposite side edges and with a portion of the second section overlying the first section to form a pocket for a key supported by one of the sections, the outer portions of the two sections being foldable to cover keys suspended on the back of the first section opposite to the 10 first named flap.

2. In a key case, a flexible sheet, a flap intermediate the opposite side edges forming one wall of a selective key compartment and the opposite edges of the sheet being foldable

in directions away from the flap to form one 15 wall of a second compartment for a plurality of keys at the other side of the sheet and said compartments having means to respectively support one, and a multiple number of keys.

3. In a key case formed of a flexible sheet, key 20 holding devices intermediate the opposite side edges of the sheet, said sheet embodying end flaps foldable upon each other to overlie said key holding devices, and a flap at the opposite side of the sheet said flap carrying a selective 25 key holding device.

ARTHUR H. MERRILL.
